JEDDY D. NIXON AND GERALD R. LIVERGOOD, OF HOUSTON, TEXAS.

PUMP.

Application filed November 29, 1924. Serial No. 752,856.

This invention relates to new and useful improvements in a pump.

One object of the invention is to produce a pump of the character described adapted for use in pumping wells and embodying a working barrel and a plunger therein having surrounding packing, and including also means for adjusting said packing to the plunger without the necessity of pulling the pump to the surface of the ground, or even stopping the operation thereof for the purpose of making said adjustment.

Another object is to produce a pump of the character described embodying means whereby the plunger packing may be properly adjusted to the plunger through the rotation, or manipulation, of the pump tubing, as will be hereinafter more specifically explained.

A further object of the invention is to produce a pump, as described, embodying a construction whereby the plunger-operating rods will turn with the tubing, in making the packing adjustments, above referred to, so as to distribute the wear on said rods and tubing, as will be explained hereinafter more in detail.

A further feature of the invention resides in a novel type of casing engaging anchor, whereby the stationary part of the pump may be anchored against rotation in effecting the adjustment of the packing about the plunger.

A still further feature of the invention resides in a novel construction whereby the fluid pressure on opposite sides of the packing may be equalized, in withdrawing the plunger from the working barrel, to the end that the packing will not become displaced, by unequal pressures, during the operation of withdrawing said plunger.

With the above and other objects in view this invention has particular relation to certain novel features of construction, operation and arrangement of parts an example of which is given in this specification and illustrated in the accompanying drawing, wherein:—

Figures 1, 2, 3 and 4 are vertical sectional views showing the complete pump in sections from the top downward.

Figure 5 shows a side view of the anchor, partly in section.

Figure 6 shows a sectional view, of the anchor, taken on the line 6—6 of Figure 5, 55 and

Figure 7 shows a transverse sectional view thereof, taken on the line 7—7 of Figure 5.

Referring now more particularly to the drawings, wherein like numerals of reference designate similar parts in each of the figures, the numeral 1 designates the well casing to the upper end of which the conventional casing head 2, is secured.

Beneath the casing, in the well, there is 65 the liner 3, smaller in diameter than the casing, and whose upper end projects up into the casing. A conventional packer 4 is interposed between the casing and liner to form a fluid tight joint.

The casing head 2 has a central vertical opening 5, and around this opening, in the upper side of the casing head, there is a counter-sunk annular seat 6 to receive the supporting ring 7. The pump tubing and 75 pump, hereinafter described in detail, are suspended from the casing head, by this ring.

There is an elongated tubular gland 8, 80 fitted through the ring 7, from the lower end of which the pump tubing is suspended.

Above the casing head the gland 8 has an outwardly extending annular shoulder 9 and between this shoulder and the ring 7 there are the annular bearing plates 10 and 11, 85 the former of which rests on the ring 7 and the latter of which forms a support for the shoulder 9 and the anti-friction bearings.

12 are interposed between these plates. These plates, and the bearings between them, are held in place on the gland 8 by means of a key ring 13 which is seated in an annular key way 14 around said gland 8 just beneath the plate 10. The shoulder 9 has one or more sockets 15, to receive an 90 operating rod, or handle, by means of which the gland 8, and the tubing beneath may be turned.

Leading upwardly from the gland 8 there 100 is a discharge tube 16, with which the discharge line (not shown) is connected in any conventional manner. The lower end of this tube 16 has an outwardly extending annular flange 17, which fits within the upper end of the gland 8 and rests on an 105 annular bearing shoulder 18 therein. On

this flange 17 rests the annular packing 19 which is fitted within the upper end of the gland 8 and is held clamped therein by means of the clamp nut 20, which is threaded over the upper end of the gland 8. A fluid tight swiveling connection between the gland 8 and the discharge tube is thus provided.

The pump barrel is suspended in the well by means of the tubing 21 whose upper end 10 is threaded into the lower end of the gland 8. This tubing may be made up of joints, or sections, and may be of any required length to locate the pump at the desired point in the well. The pump will usually 15 be located down in the liner 3, near the oil bearing strata.

Threaded onto the lower end of the tubing 21 there is a nipple 22 and the upper end of the pump working barrel is threaded onto 20 this nipple. This working barrel may be formed of two tubular sections, an upper and lower section, designated, respectively by the numerals 23 and 24. For convenience in assembling the upper section is formed of 25 two parts screwed together, as at 25. Beneath this connection the lower part of section 23 is thickened inwardly and internally threaded to receive the outwardly threaded upper end of the lower section 24, which 30 telescopes, and is threaded, therein.

Packing 26, is interposed between the sections of the working barrel, at the lower end of the outer section, and is held in place by the gland 27 which surrounds the lower section 35 of the barrel and is screwed up into the lower end of the upper section thereof, against said packing. A fluid tight joint is thus formed which will also exclude grit, and the like and thus protect the threads 40 connecting the working barrel sections. The lower end of the gland 27 is beveled, as at 28, to prevent the barrel from hanging on any internal projections in the casing or liner.

There is a tubular plunger 29 in the working barrel. The upper end of this plunger works through the nipple 22 and threaded into it is the tubular body 30, of the traveling valve. The upper end of this body carries the usual annular valve seat 31 which is 45 clamped in place by the lower end of the valve cage, 32, threaded onto the upper end of said body, and said seat is controlled by an upwardly opening ball valve 33, which is confined by said cage. The plunger is 50 reciprocated by means of the pump rod 34 whose lower end is connected to said cage and whose upper end is connected to the conventional pump-operating means (not 55 shown) at the ground surface. This pump rod has a swiveling joint 35, preferably located above the casing head.

The inside of the working barrel carries 60 suitable packing, as 36, which surrounds the plunger 29, and is preferably formed of 65 fabric packing rings. This packing is con-

fined between the nipple 22, above, and the sleeve 37 beneath, said sleeve being fitted within the working barrel and resting on the upper end of the lower section, 24, thereof. The nipple 22, and sleeve 37 form abutments 70 to confine said plunger packing, and there are metal washers, 38, 38 located between said respective abutments and the adjacent ends of the packing 36. As the packing and plunger wear, incident to the operation of 75 the pump the packing may be adjusted about the plunger to take up the wear, as will be hereinafter explained.

Connected to the lower end of the working barrel there is a well screen 39, formed of 80 one or more tubular sections, suitably perforated, in any conventional manner, to permit the inflow of the surrounding fluid. The upper end of this screen is un-perforated and has a contracted section 40, which is downwardly tapered to form a downwardly conveying seat in which is located a tubular lead seal 41.

A standing valve seat 42 is sustained by the seal 41, and is controlled by the upwardly opening valve 43 which is confined by the standing-valve cage 44, all located within the upper end of the screen 39, said upper end forming a casing, or housing, 45, for the standing valve structure. Screwed 90 into the lower end of the valve seat there is a depending inlet pipe 46 which is fitted through the seal 41 and projects down into the screen 39.

Attached to the lower end of the screen 100 there is a tubular spider 47, having the lateral concaved recesses 48, and located in these recesses are the eccentric dogs 49. These dogs are of a general cylindrical contour, and each is mounted eccentrically on a 105 shaft 50 whose respective ends are anchored in the end webs 51, 52 of the spider. The range of rotation of each dog is limited by the spaced stops 53, 53, formed on the lower end of each dog and adapted to contact with a stud 54 carried by the web 52 and located between said stops. One end of each dog 110 has a recess, as 55, in which is located a coil spring 56 which surrounds the rod 50 and whose ends are outwardly turned. One of 115 said outturned ends is fitted into a socket in the adjacent web 51 and the other is fitted into a socket, as 57 in the adjacent end of the dog. A plurality of these last named 120 sockets are provided so as to make provision for adjusting, or varying the tension on said spring.

The dogs being mounted eccentrically, in effect, one side of each dog forms a cam 125 which is fluted lengthwise, forming engaging teeth, as 58, and the tension of the springs normally holds said cams in expanded, or outward position, in readiness to engage with the surrounding pipe, or liner. The respective ends of the dogs are con- 130

- tracted, or tapered, as shown, and the lower taper, of each dog is also fashioned in the form of a spiral, for a purpose to be herein-after explained. Depending from the spider 47 there is the usual section of tubing, or pipe, 59, which extends down well to the bottom of the bore and is provided to limit the drop of the pump mechanism, should it be accidentally released from above.
10. The pump mechanism is assembled, as shown and gradually let down into the well, with the dogs 49, in outward, or expanded position. The pipe 59 enters the liner 3 and serves as a guide for the pump to enter.
15. The lower ends of the dogs 49, as stated are tapered, and their spiralled formation is such that as they enter the liner they will be forced around into inward, or contracted, position, so that they will enter the liner, 20. and the springs 56 yield to permit this movement, and are thereby placed under further tension with the effect that they hold the fluted cam faces of the dogs in secure contact with the liner walls to instantly engage 25. with said walls in case the spider is subjected to torsional strain. The pump is lowered in the well to the desired point, and there anchored, as shown.

In operation the plunger is reciprocated, 30 up and down, in any well known manner, the plunger 29 working through the packing 36. Eventually the packing, and also the plunger, will wear so as to permit leakage past the plunger, between it and the packing. The 35 efficiency of the pump will thus become impaired, necessitating the adjusting, or tightening, of the packing about the plunger. This may be accomplished by inserting a rod, or handle into one of the sockets 15 and 40 turning the tubing 21 to the right. The dogs 49 will at once engage with the liner and anchor the lower section 24. of the working barrel, against turning. This rotation of the tubing will cause the upper working 45 barrel section to telescope further down on the lower section, in effect drawing the abutments against the ends of the packing 36 closer together and compressing the packing to take up said wear. This work may be 50 easily accomplished without stopping the pump, and the packing will thus be adjusted to a nice fit around that portion of the plunger which is worn.

It is well known that the bore of a well 55 particularly of a deep well, is usually sinuous, so that the tubing will usually have a number of bends, or curves, and these are sometimes so decided that the pump rod will often have to bend or curve to follow the 60 course of the tubing. Consequently as the rod is reciprocated it will wear against the inner sides of the bends in the tubing and will not only wear the tubing, at these points, but will itself be also worn away by the fric-

tion. For that reason the rod has the swiveling joint 35, so that as the tubing is turned, the plunger, and rod beneath said joint, will also turn, thus bringing other parts of the tubing wall and rod into frictional contact to secure uniformity of wear all the way 70 around.

It sometimes becomes necessary to pull the plunger out for repairs, and in withdrawing it, it becomes necessary to equalize the pressure against the upper and lower ends of the 75 packing 36; otherwise the normal pressure of the fluid against the upper end of the packing, being greater than the normal pressure in the working barrel, during this pulling operation, would displace the packing as 80 soon as the plunger clears it, in being withdrawn. In order to equalize this pressure a port 60, is provided in the plunger and so located that it will clear the upper end of the packing 36 and permit the entrance of 85 the fluid, from within the tubing 21, into the working barrel, to equalize the pressure before the plunger has cleared the lower end of said packing.

When the plunger has been withdrawn the 90 standing valve may also be pulled out, if necessary, by the use of a suitable tool for this purpose, without disturbing the seal 41, and these parts when repaired, may be as readily replaced for the further operation of the 95 pump.

What is now considered the preferred form of the pump has been shown and described, but it is apparent that mechanical changes may be made and certain parts rearranged without impairing the efficiency of the pump; as for example the anchor shown might be located elsewhere, in the structure, than at the point as illustrated, and various other, mechanical changes and rearrangements might be made without departing from the principle of the invention or the scope of the appended claims.

What we claim is:—

1. A pump including a working barrel, a plunger therein, packing in said barrel around the plunger, means abutting against the upper and lower ends of the packing, rotatable tubing for suspending the pump in a well bore, and operative connections through which the tubing may be employed by rotating the same to rotate the upper abutment and thereby to adjust said packing about the plunger, through said abutting means.

2. A pump including a working barrel, a plunger therein, packing in said barrel around the plunger, upper and lower abutments confining said packing, means for anchoring the lower abutment against rotation, tubing suspending the pump in a well bore, means having connection with said tubing and adapted to be operated thereby to effect the relative rotation of said abutments and

thereby accomplish the adjustment of the packing about the plunger, through said abutments.

3. A pump including a working barrel, a tubing to the lower end of which the barrel is connected, a plunger in said barrel, packing in the barrel around the plunger, means adapted to be actuated by the tubing when the tubing is rotated, and through which the packing may be adjusted about the plunger, said means embodying end abutments operative against the ends of the packing and an anchor adapted to engage the walls of the well bore to secure one of said abutments 15 against rotation.

4. A pump including a working barrel, a tubing to the lower end of which the barrel is connected, a tubing support to which the tubing is rotatably connected, a plunger in 20 the barrel, packing in the barrel around the plunger, means for rotating the tubing, means adapted to be actuated from the tubing, when the latter is rotated, and through which the packing may be adjusted about 25 the plunger.

5. A pump including a working barrel, a tubing to the lower end of which said barrel is attached, tubing suspending means, with which the tubing has a swiveling connection, 30 a plunger in the barrel, packing in the barrel around the plunger, abutments disposed to confine the packing and one of which is fixed with respect to the other, means for anchoring said fixed abutment, 35 means through which said tubing operates, when rotated, to effect the adjustment of said packing, about the plunger, through said abutments.

6. A pump including a working barrel, 40 formed of sections having a threaded connection, a plunger therein, packing in the barrel around the plunger, abutments in the barrel carried by the respective sections, and confining said packing, means adapted to engage the walls of the well bore for anchoring one of said sections against rotation, means for rotating the other section.

7. A pump including a working barrel 50 formed of sections having a threaded connection, a plunger therein, packing in the barrel around the plunger, abutments above and below the packing for confining the same, one of said abutments being carried by the corresponding barrel section, the 55 rotation of one barrel section relative to

the other being effective to adjust said abutments relative to each other and to thereby adjust the packing about the plunger, and an anchor for engaging the walls of a well bore to secure one of said sections against 60 rotation.

8. A pump including a working barrel formed of sections having a threaded connection, a plunger therein, packing in the barrel around the plunger, abutments above 65 and below the packing for confining the same, one of said abutments being carried by the corresponding barrel section, the rotation of one barrel section relative to the other being effective to adjust said abutments relative to each other and to thereby adjust the packing about the plunger, an anchor carried by one of said sections and adapted to engage the wall of a bore for holding said section against rotation, and 70 a tubing to which the barrel is attached and through which the other section may be rotated.

9. A pump including a working barrel, a tubing to the lower end of which the barrel is connected, a plunger in said barrel, packing in the barrel around said plunger, abutments carried by the barrel between which the packing is confined, means for engaging with the wall of the well bore and 80 anchoring one of said abutments against rotation therein there being connections through which said abutments may be adjusted by the rotation of the tubing to effect the adjustment of the packing about 85 the plunger.

10. A pump including a working barrel, a rotatable tubing to the lower end of which the barrel is attached, means from which the tubing is suspended, a plunger in the barrel, 90 packing in the barrel around the plunger, said barrel embodying relatively rotatable means confining said packing, means adapted to engage the wall of a well bore for anchoring one of said confining means against 95 rotation, while the pump is suspended in the bore, the other of said means being rotatable with the tubing, and an operative connection through which the tubing acts, when rotated, to effect the adjustment of the packing about 100 the plunger through said confining means.

In testimony whereof we have signed our names to this specification.

JEDDY D. NIXON.
